CHAMFER STRIP

William E. Mitchell, Altoona, Pa.

Application July 20, 1953, Serial No. 369,025

3 Claims. (Cl. 25—118)

This invention relates to a chamfer strip and particularly to a chamfer strip arranged as a frame to be mounted in the mold form to provide a chamfer at the top of a casting made therein.

In the construction of concrete structures in mold forms, it is frequently desirable to provide a chamfer adjacent the edges of the casting so that it will not require further finishing and so that the edges will be quite rigid and strong in operation and not be crumbled away by accidental impact therewith.

In order to provide such chamfer strips, the present invention provides a form adapted to fit within a mold form and to provide a triangular form adjacent the edge of the finished material so that a chamfer will be formed in the finished casting. This is accomplished by means of a triangular chamfer strip, with strips arranged as elements of a frame adapted to slide within the mold form and having loops or ears for supporting the frame in position in the mold form and having reinforcing bars extending across the finished frame with the bottoms of the reinforcing bars being elevated out of the plane of the frame so that finishing tools or the like may be readily inserted thereunder. Preferably, the corners of the frame are also cut away or mitred so that perpendicular chamfer strips in the mold may be accommodated therein.

The present application is in part a continuation of applicant's copending application, Serial No. 199,293, now Patent No. 2,650,411, filed December 5, 1950.

It is accordingly an object of the invention to provide an improved chamfer strip.

It is a further object of the invention to provide a chamfer strip arranged as a form or frame to be received in a mold form.

It is a further object of the invention to provide a chamfer strip so arranged that the top of a casting made therein may be readily finished.

Other objects and many of the attendant advantages of the present invention will be apparent from the following detailed description, taken in conjunction with the accompanying drawing in which:

Figure 1 is a sectional elevation of a chamfer strip in position in a mold form;

Figure 2 is a perspective view of a chamfer strip according to the invention;

Figure 3 is a similar view of a modified chamfer strip;

Figure 4 is a cross-section through an element of the chamfer strip taken substantially on the plane indicated by the line 4—4 of Figure 2; and,

Figure 5 is a fragmentary plan of a corner of the frame showing the cut-away or mitre to allow the frame to fit in a form having a corner chamfer strip already therein.

In the exemplary embodiment according to the invention, a mold form side constructed of a plurality of channels 10 is spaced from another side of the mold form constructed of a channel 12 having a bulkhead 14 connected across the open side so that it forms a substantially closed device. Such mold forms being disclosed in my

2

copending application, Serial No. 267,044, now Patent No. 2,650,410, filed January 18, 1952.

The chamfer strip itself comprises a plurality of elements, each element being constructed as an angle member 20, and a filler or cover strip 22. The filler or cover strip 22 may be in the form of a metallic strip, welded or otherwise secured across the open face of the channel, or preferably as shown in Figure 4, the filler may be a triangular wood strip 24, secured within the open face of the channel by any suitable means.

A plurality of chamfer elements are developed into a frame including a pair of longitudinal frame members 28 and 30 joined together by means of cross or end members 32 and 34 to provide a substantially rectangular frame to be inserted into the mold form as illustrated in Figure 1. Preferably the corners of the device are rigidly connected, together by welding or the like so that the frame is a rigid unit adapted to be slid into the top of the mold form. Obviously, the frame instead of being rectangular may be of any desired shape to fit within a mold form.

Also, as shown in Figure 3, the frame members may be constructed of curved side strips 36 and 38 having bends 40 and 42, therein so that the central portion of the chamfer strip is elevated above the end portions 32 and 34. Obviously, the chamfer strips may be provided with more than one bend 40 and 42, or the entire strip may be curved from end to end to form an arch or other curved surface if desired. Preferably, the corners of the frames are cut away or mitred, as shown at 48, to provide a cut-away or mitred corner to accommodate a vertically extending chamfer strip which will be placed in the main form.

In order to properly locate the chamfer strip in a mold form, a plurality of ears or hanger members are preferably connected in pairs to the frame device, and while any suitable ears may be used, I prefer to use a loop device constructed of a metallic rod bent into narrow U-shaped formation to provide a hanger 50 having a longitudinally extending slot 52 to receive the shank of suitable adjusting bolts. The lower ends of the legs 54 and 56 of the loop 50 are angulated outwardly to provide feet 58 which lie on the top of the element constituting the frame and are rigidly connected thereto by any suitable means, such as welding. Preferably the loop 50 extends upwardly substantially as a continuation of the outer face of the element 20, and is substantially flush therewith. In securing the device in the mold form, the loop 50 will extend adjacent the surface of the mold form and be secured thereto by means of suitable fasteners such as the bolts 60 which extend through suitable apertures 62 in the mold form and are secured to the loops 50 by means of suitable fasteners such as the nut 64.

The loops 50 are preferably provided in pairs on opposite sides of the framework, and reinforcing bars 70 extend between the legs 54 and 56 of the loops 50 and extend transversely across the framework with the ends of the bars being permanently and rigidly connected to the legs 54 and 56 of the loop by any suitable means such as welding. The underside of the reinforcing bar 70 is cut away as at 74 to provide an arched upwardly bottom surface so that the bottom surface of the reinforcing bar 70 is in upwardly spaced relation to the top surface of the frame. This upwardly arched condition of the reinforcing bar permits a trowel or other working tool to be inserted under the bar to properly finish the top of the casting within the form.

In the operation of the device according to the invention, suitable chamfer strips will be constructed for the standard mold sizes and for the standard mold tops. Preferably the chamfer strip will be of the proper length to fit the shorter mold forms and to be utilized in a larger

mold form, the form will simply be cut across and separated to a mold form, and triangular wooden strips or filled metal angles will be inserted between the ends of the cut-apart frame to lengthen it to the desired amount. The frame will be supported at any suitable point in the mold form by means of the bolts 60 inserted in the aperture 62 in the mold form, and tightened so as to be in little danger of displacement during the pouring of the casting. Preferably the chamfer strip will be coated with a transparent plastic, usually in the form of a varnish or paint to protect the outer surface of the material of which the strip is constructed so that it will not rust and so that no undesirable coloration will be transferred from the strip to the cast material. Also, it is preferable to spray the mold form and the chamfer strip with a light oil immediately previous to constructing the casting therein so that there will be no danger of sticking or impacting the mold.

For purposes of exemplification, a particular embodiment of the invention has been shown and described according to the best present understanding thereof. However, it will be apparent to those skilled in the art that many changes and modifications in the arrangement and construction of the parts thereof may be resorted to without departing from the true spirit and scope of the invention.

What is claimed as new is as follows:

1. A chamfer strip for use in a mold form comprising a frame adapted to be positioned in a mold form, said frame being triangular in cross-section, narrow U-shaped hangers, angulated ends on the legs of said hangers, said angulated ends being rigidly secured on the top of the frame, said U-shaped hangers extending substantially flush with the outer edge of said frame.
2. A chamfer strip for use in a mold form comprising a frame adapted to be positioned in a mold form, said

frame being triangular in cross-section, narrow U-shaped hangers, angulated ends on the legs of said hangers, said angulated ends being rigidly secured on the top of the frame, said U-shaped hangers extending substantially flush with the outer edge of said frame, reinforcing members extending across said frame, the ends of said members being received between the legs of said U-shaped hangers and rigidly secured thereto, the bottom of said reinforcing members being displaced upward out of the plane of said frame.

3. A chamfer strip for use in a mold form comprising a frame adapted to be positioned in a mold form, said frame being triangular in cross-section, narrow U-shaped hangers, angulated ends on the legs of said hangers, said angulated ends being rigidly secured on the top of the frame, said U-shaped hangers extending substantially flush with the outer edge of said frame, reinforcing members extending across said frame, the ends of said members being received between the legs of said U-shaped hangers and rigidly secured thereto, the bottom of said reinforcing members being displaced upward out of the plane of said frame, the corners of said frame being cut away to receive a triangular chamfer member.
